(57) **CLAIM**

The ornamental design for a Y-component with peg for a student desk.

DESCRIPTION

FIG. 1 is a perspective view of the Y-component with peg for a student desk.

FIG. 2 is a side view of the Y-component with peg for a student desk.

FIG. 3 is a perspective view of a Y-component with peg for a student desk, the broken lines are for environmental purposes only and form no part of the claimed design.

FIG. 4 is a front view of a Y-component with peg for a student desk.

FIG. 5 is a back view of a Y-component with peg for a student desk; and,

FIG. 6 is a right side view of a Y-component with peg for a student desk; the other side being the mirror image thereof.
